(57) **CLAIM**

The ornamental design for an anti-theft hanging packaging for tools, as shown and described.

DESCRIPTION

FIG. 1 is a perspective view of an anti-theft hanging packaging for tools showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof; and,

FIG. 8 is a cross-sectional view thereof.

The broken lines in FIGS. 1-7 depict unclaimed portions of the anti-theft hanging packaging for tools that form no part of the claimed design.
